PANTS

Trent B. Terry, Charlottesville, Va.

Application September 27, 1941, Serial No. 412,670

3 Claims. (Cl. 2—227)

1

This invention relates to a pants garment and more particularly to pants for pajamas, slacks, lounging suits and the like.

This invention comprises a development of the garment shown in my prior patent, Reissue 21,803, wherein there is disclosed a short-legged garment, the seat, abdominal and leg regions of which are constituted by a blank of material so dimensioned as to be obtainable from a strip of woven cloth of ordinary width, with the weft of the cloth preferably running vertically in the blank. The object of the present invention is to obtain the advantage of the prior arrangement, even in a long-legged garment without necessitating increase in the weft-wise width of the material from which the blanks are cut.

As in the above noted prior patent, it is intended to provide a garment wherein the straight of the material from the lower ends of the pants to the waistband is disposed on the bias with the lines of the material in downwardly convergent V-formation. In the present instance, however, it is proposed to provide a main blank forming the hip, crotch and leg regions of the garment and a subsidiary blank forming the abdominal and upper hip region of the garment, the subsidiary blank maintaining the bias formation of the cloth and the downwardly converging V-formation of the entire garment. Additionally it is proposed to provide a bias-cut garment having a plurality of blanks stitched together and wherein the lines of stitching connecting the blanks are also disposed in downwardly converging V-formation whereby to avoid any constraining or constricting of the relatively non-stretchable regions extending horizontally around the hips or lower abdomen of the wearer.

A further object of the invention is to provide a pair of long-legged pants of woven material so formed as to take full advantage of the selvedge of the material in the formation of a seam extending around the garment, yet avoiding any binding effect against the wearer which ordinarily results from increased resistance to stretch of woven material along the seams. In keeping with this objective, it is herein proposed to provide a garment formed by a series of blanks, from top to bottom, but having no seams, and no "straights" of material extending horizontally entirely around the body of the wearer.

Other objectives include the formation of a garment wherein the material has a V-forming design characteristic which is both decorative and functional, and which may readily be cut and assembled by relatively unskilled labor.

2

These and other objects will appear from the following specification and drawings in which:

Fig. 1 is a front elevation of the completed garment.

5 Fig. 2 is a rear elevation of the garment shown in Fig. 1.

Fig. 3 is a plan view showing the lay-out of the pattern on the piece of material.

10 Fig. 4 is a plan view of a composite blank at one stage of the formation of the garment.

Fig. 5 is a detail, in perspective, illustrating a step in forming the fly.

15 Fig. 6 is a section taken along the lines 6—6 of Figure 5.

Fig. 7 is a perspective showing the fly element shown in Figs. 5 and 6 as it would be seen if removed and opened.

20 Fig. 8 is a detailed showing of the completed fly element shown in Figs. 5 to 7.

Fig. 9 is a perspective illustrating one step in forming the waistband.

25 Fig. 10 is an end view of the waistband as illustrated in Fig. 9; and

Fig. 11 is a front elevation of the garment immediately prior to completion.

30 Referring first to Figs. 1 and 2, the pajama garment illustrated is comprised of a substantially triangular waistband 2 which overlies the upper abdominal region of the wearer, an intermediate abdominal region 4, a lower abdominal region 5, a fly 6 extending vertically along the median line of the garment, a crotch 8, left and right legs 10 and 12 (as seen looking at the front) and left and right cuffs 14 and 16. In the back of the 35 garment there is an elastic knit belt 18 and a full seat 20. It should be noted that with the exception of the cuffs and the waistband, the design lines 21, which extend along the straight of the material, preferably the warp, are disposed 40 across the garment in downwardly converging V-formation when viewed from the front, that the exposed edge of the fly extends vertically along the median line of the garment and that seam 70, described below, joining the intermediate and lower abdominal regions of the garment, forms a downwardly convergent V in the front.

45 Figs. 3 and 4 diagrammatically illustrate the formation of the garment, the various elements being shown on a reduced scale and wherein seat 50 20, crotch 8, legs 10 and 12, and lower abdominal region 5 of the garment are formed from a main blank 24 cut from a strip of material 22 having the straight of the fabric running parallel to selvedges 25, 27 and comprising upwardly convergent left and right side edges 26 and 28, re-

spectively, a straight top edge 30 extending along selvedge 25, left and right downwardly inclined edges 32 and 34 extending laterally at each side of the principal, straight portion 30 and connecting the top edge 30 with the side edges. At the lower side of the blank are left and right central bottom edges 36 and 38 formed by an inverted V-shaped gap between left and right leg bottom edges 49 and 42, respectively.

The intermediate abdominal region 4 of the garment is formed from left and right abdominal blanks 44 and 46, respectively, the left abdominal blank having an inclined left side edge 48, a horizontal top edge 50 extending along the straight of the material, a concave top edge portion 52, a vertical right hand edge 54 and a bottom edge 56 extending along the straight of the material. Conversely the right abdominal blank 46 has an inclined right edge 58, horizontal top edge 60, concave top edge portion 62, vertical left edge 64 and bottom straight edge 66, as shown best in Fig. 4.

The end edges 54 and 64 of the left and right abdominal blanks 44, 46 are stitched together as shown at 68 and the bottom straight edges 56 and 66 are stitched, so as to form a seam 70, to the straight top edge 30 of main blank 24.

The fly of the garment is formed by a W-shaped facing blank 72, having parallel left and right side edges 74 and 76, a V-notch 78 and a point 80 in the top edge, and a point 82 and V-notch 84 in the bottom edge.

Edge 76 of blank 72 is first stitched to edge 48 by stitches 86 of abdominal blank 44 while blank 72 is held flat against abdominal blank 44, and then blank 72 is folded along the line 88 between point 80 and notch 84, as shown in Figs. 5 and 6. Overlapping bottom edge of blank 72, which extends between point 82 and the apex of notch 84 are then stitched as shown in Fig. 7, which illustrates blank 72 at this stage as it would be seen if removed from blank 44. Finally blank 72 is turned partially to overlie the left-hand portion of blank 44 and edge 74 is stitched to the face of blank 44 by stitches 92 as shown in detail in Fig. 8, the lower edge of blank 72 between point 82 and edge 74 being stitched down along seam 70, as indicated at 93.

The righthand portion of abdominal blank 46 is faced with a patch 94 having side edges 96 and 98, as shown in Fig. 4. Edge 96 of the facing patch is stitched to edge 58 of abdominal blank 46, after which patch 94 is turned back along line 97 and edge 98 is stitched to abdominal blank 46 along dash lines 100.

Referring now to Figs. 9 and 10, the waistband 2 of the garment is formed by a generally triangular blank 104 having convergent edges 106 and 108, a straight top edge 110 and short parallel edges 112 and 114 connecting straight top edge 110 and converging edges 106 and 108. A second generally triangular blank 116 having converging edges 118, 120 is stitched to blank 104 as shown at 122 and an elastic belt 124 is stitched in slightly stretched condition to blank 104 by stitches 126 and 128 adjacent the ends of the belt.

The garment is assembled by stitching the edges 32 and 34 together, thus to form the frontal median line of the garment 112 as shown in Fig. 11, and thus to bring the opposite ends of seam 70 together at the front in downwardly converging V-formation.

Next converging edges 106 and 108 of blank 104 are stitched to straight top edges 50 and 60

of the left and right abdominal blanks by lines of stitches 130, 132, with the lower point of blank 104 centered in notch 78 of facing blank 72, so that the garment, at this stage, appears as in Fig. 11. Finally triangular blank 116 is brought forwardly and downwardly, the edges 118 and 120 being turned under and stitched to edges 50 and 60 of the abdominal blanks, after which the garment is finished by stitching leg edges 26, 36 and 28, 38 together by stitches 37, 39, respectively, folding and stitching cuffs 14 and 16 to the bottoms of the legs by stitches 15 and 17, and stitching elastic belt 18 to concave edges 52 and 62, the ends of belt 18 being secured to edges 112, 122 and 114, 123 of the triangles 104, 116 by stitches 138 and 140, respectively.

It is thus seen that while elastic belts 18 and 124, extending horizontally around the waist of the wearer, the front waistband section 2 limits the horizontal stretch of belt 124, thereby preventing hiking up of the garment in the front which would tend to cause binding in the crotch and to distort the V-formation. Additionally, the horizontal and vertical forces exerted in tension on legs 10 and 12 or abdominal regions 6 extend along the yieldable bias of the material rather than the straight, which is relatively non-stretchable. Particular note should be made that seam 70, except at the very center of the back of the garment, always extends at an angle to the horizontal dimensions. It has been found that with this arrangement, binding or climbing of the garment is avoided.

By the novel construction these advantages are maintained even in a multiple blank assembly in accordance with this invention, the scope of which is not limited to the precise disclosure, but only in accordance with the following claims.

I claim:

1. In a pants garment, first blank means formed of woven fabric having the major portion of the upper edge thereof extending along the straight of the fabric, downwardly divergent side edges, downwardly convergent bottom edges, and a central cut-out of inverted U-shape between said bottom edges, second blank means formed of woven fabric, said second blank means being of less width than the first blank means and having a bottom edge extending along the straight of the fabric, a seam connecting the lower edge of the second blank means to the top edge of the first blank means, said second blank means having a central concave upper edge portion and a straight upper edge portion extending along the straight of the fabric at each side of said concave upper edge portion, means securing said side edges of said first blank means to the edges of said cut-out to form the legs of said garment, the free ends of said seam being disposed in downwardly converging relationship across the front of the garment, the ends of said second blank means forming the fly of said garment, facing means on the ends of said second blank means, a substantially triangular waistband having a downwardly disposed apex, and a second seam connecting the lower edges of said waistband to the straight upper edge portions of said second blank means.

2. The combination claimed in claim 1, the top edge of said first blank means having laterally extending portions at each side, respectively, of said major portion, said laterally extending portions being secured to one another to form the

lower portion of the frontal median line of the garment.

3. The combination claimed in claim 1, the top edge of said first blank means having laterally extending portions at each side, respectively, of said major portion, the side edges of said second blank means being substantially parallel with the side edges of said first blank means, one of said facing means comprising a piece of fabric having substantially V-shaped upper and lower edges and parallel side edges, one of the last-named side edges being stitched to one end edge of said second blank means and the adjacent portion of the V-shaped bottom edge being stitched to the adjacent laterally-extending portion of the top edge of said first blank means, the V-shaped upper edge of said piece being secured to the apex of said waistband.
